ATTORNEY

UNITED STATES PATENT OFFICE.

MIGUEL GONZALEZ, OF NEW YORK, N. Y.

ICE BOX.

1,425,854.

Specification of Letters Patent. Patented Aug. 15, 1922.

Application filed August 27, 1921. Serial No. 496,004.

To all whom it may concern:

Be it known that I, MIGUEL GONZALEZ, a citizen of Venezuela, and resident of New York city, in the county of New York and 5 State of New York, have invented certain new and useful Improvements in Ice Boxes, of which the following is a specification.

The invention relates in general to an ice box of the cabinet type and particularly relates to an ice box of the type in which a 10 large volume of water is designed to be stored and filtered for potable purposes and which may be cooled for drinking purposes.

The present invention constitutes an improvement over the form of ice box disclosed in my patent No. 1,367,693, February 15, 1921.

In the previous patent it was noted that the available water in some locations is not 20 suitable for drinking purposes and it was suggested that the water be stored in the box and chemically treated before it was used. With some characters of waters it is necessary to filter the water either with or 25 without the chemical treatment previously suggested.

The present disclosure features the providing of an ice box designed to resemble conventional forms of such articles of household furniture and which can be utilized to 30 store large volumes of water, to filter and cool the water as it is used, and at the same time to preserve the external appearance so that the box will appear to be of the usual 35 form.

The difficulty with such forms of ice boxes is that the water storing space must be large in order to store the necessary amount of water and where large volumes of water are 40 caused to pass through the usual small filter the sediment rapidly accumulates in any usual form of filtering device and must be replaced or cleaned too frequently to be of any commercial value.

One of the objects of the present invention is to provide a cabinet form of ice box of the type outlined in which a relatively 45 large water storing compartment is provided without materially modifying the external appearance of the box and which features a slow acting filtering partition which can be made of relatively large area to accommodate the large compartment and which can be readily installed in position 50 to replace a contaminated partition.

Incidental to the desire to provide a form of device which can be readily cleaned, the

invention also features a form of water conduit which includes a cooling coil which can be readily removed for cleaning or replacing the old coil with a new unit. 60

Various other objects and advantages of the invention will be in part obvious from an inspection of the accompanying drawings and in part will be more fully set forth 65 in the following particular description of one form of mechanism embodying my invention, and the invention also consists in certain new and novel features of construction and combination of parts hereinafter 70 set forth and claimed.

Referring to the accompanying drawings:

Figure 1 is a perspective view showing a preferred embodiment of my invention; 75

Figure 2 is a transverse vertical sectional view taken through the under portion of the box shown in Figure 1 and

Figure 3 is a detailed view in side elevation showing the water conduit, also shown 80 in dotted outlines in Figure 1.

In the following description and in the claims, parts will be identified by specific names for convenience of expression but they are intended to be as generic in their 85 application to similar parts as the art will permit.

In the drawings, there is shown an up-standing wooden cabinet including a front side 12, a rear side 13, and end sides 14, 90 preferably panelled and otherwise designed to simulate ice box constructions now in general use. The interior of the cabinet is divided into two major compartments by means of a partition 15 which forms a lower 95 ice containing and storing compartment 16 and an upper water containing compartment 17. The water containing compartment is lined with a metallic lining 18 and is open at the top. A cover 19 constitutes 100 the top of the box and a closure for the compartment 17. A plurality of supporting lugs 20 project inwardly from the sides of the compartment 17 and serve as supports for a metal tank 21. This tank is designed 105 to contain unfiltered water and has a bottom 22 which is spaced from the bottom of the compartment so as to divide the water containing compartment into an upper unfiltered water compartment 23 and into a lower 110 filtered compartment 24. In those conditions where the water is used about as rapidly as it is filtered the compartment 24 will be relatively small as shown in Figure

2 but in those conditions where it is desired to store a relatively large amount of filtered water the unfiltered water compartment will be of relatively smaller proportion than illustrated.

5 The bottom 22 is provided with an opening 25 which is outlined by a depressed upwardly facing seat 26.

10 A slab of filtering material, such as unglazed sand-stone 27 is positioned on the seat and the stone, if desired, may be cemented into place with some sort of soft cement.

15 The filtered water is discharged from the box through a conduit, part of which is formed into a coil 30 which also constitutes a supporting ledge for the ice and is disposed in an ice pan 31. It is found that with devices of this character and irrespective 20 of the efficiency of the filtering system it is necessary to frequently clean the coil and for this purpose the coil is herein shown to be removable as a unit while leaving the ends securely fixed in place in the box. The conduit includes an intake pipe 32 opening through the bottom of the water compartment and fixed in position in the box. For the purpose of drawing unchilled water from the box the pipe 32 is provided 25 with an extension 33, projecting forwardly therefrom, through the front of the box and terminating in a faucet 34. Similarly the discharge end of the water conduit is in the form of a pipe 35 fixed in position in the box, projecting through the front side thereof and terminating in a cool water faucet 36. Both faucets are above the level of the ice supporting coil and are below the bottom of the filtered water compartment 30 thereby to permit water to flow by gravity 40 from the compartment and to permit water to accumulate in the coil to cool the water for drinking purposes. The coil 31 is provided with upturned ends, and are coupled to the pipes 32 and 35 by means of readily manipulated unions 37.

45 In operation it is understood that water from the spring, river or city supply is poured into the unfiltered water compartment and is allowed to slowly percolate through the stone filter constituting the bottom of this compartment. By selectively opening the faucets the water may be withdrawn, either directly from the filtered water compartment or from the cooling coil.

50 When the filter stone becomes contaminated it will be broken away from its seat and a new filter substituted as suggested. 60 As the slabs are large in area and in fact are made as near as possible coextensive with the bottom of the unfiltered water-containing compartment relatively small amounts of water are passed through unit 65 areas and in this way the life of the filter is

prolonged even though the box accommodates relatively large volumes of water.

Securing the ends of the water conduit in place has the advantage of locating these parts fixedly in the box, thus eliminating 70 the tendency to leak at the connections to the box and at the same time permits the removal of the coil portion which is the portion most liable to become damaged.

75 While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

80 Having thus described my invention, I claim:

85 1. An ice box provided with a horizontally disposed partition forming the interior of the box into an upper water containing compartment and a lower ice containing compartment, said water containing compartment provided with a horizontal partition constituting a filter and forming an upper unfiltered water compartment and a lower filtered water compartment, a water conduit including a coil within the ice containing compartment, said conduit having its intake end opening from the filtered water compartment and having its discharge end below the water containing compartment.

95 2. A cabinet ice box provided with a horizontally extending partition forming a water containing compartment, said compartment provided with a partition dividing the same into an upper unfiltered water chamber and a lower filtered water compartment, said second partition constituting a removable insert in the water containing compartment and formed in part by a slab of filtering material and means for 100 drawing off the water from the lower filtered water compartment.

105 3. A cabinet ice box provided with a horizontally extending partition dividing the interior into an upper water containing compartment and a lower ice containing compartment, said upper water containing compartment provided with another partition dividing the same into an upper unfiltered water chamber and a lower filtered 110 water compartment, said second partition provided with an opening, a slab seat outlining the opening, a slab of filtering material located on said slab seat and a water cooling coil in said ice chamber supplied 115 from said filtered water compartment.

120 Signed at New York city in the county of New York and State of New York this 19th day of August, A. D. 1921.

MIGUEL GONZALEZ.
